UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

DESIGN FOR A PLANE-BODY.

46,446.

Specification for Design.

Patented Sept. 22, 1914.

Application filed July 11, 1913. Serial No. 778,595. Term of patent 14 years.

To all whom it may concern:

Be it known that I, ALBERT A. PAGE, a citizen of the United States, residing in East Haven, county of New Haven, and State of Connecticut, have invented a new, original, and ornamental Design for a Plane-Body, of which the following is a specification when taken in connection with the accompanying drawing.

In the drawing, Figure 1 is a side elevation of a plane body embodying my design, Fig. 2 is a top plan view of the plane body, and Fig. 3 is a front elevation of the same.

The drawing shows a plane having a stock or body portion with a handle at one end and a knob at the other. The knob which is located at the forward end of the plane

merges into the base of the stock so that the forward edge of the plane is a continuous curved surface carrying out the configuration of the base of the knob. The handle located at the end of the plane also emerges into the stock and is formed with an acute beveled edge, which extends from the lower portion of the handle directly to the bottom line of the base.

What I claim is:

The ornamental design for a plane body, substantially as shown and described.

ALBERT A. PAGE.
